PRODUCTION OF POLYCYCLIC COMPOUNDS
Lawrence G. Cannell, Lafayette, Calif., assignor to Shell Oil Company, New York, N.Y., a corporation of DelawareNo Drawing. Filed Mar. 30, 1964, Ser. No. 355,888
6 Claims. (Cl. 260—666)

This invention relates to a novel class of polycyclic organic compounds and to a method for the production thereof. More particularly, it relates to novel saturated and ethylenically unsaturated bicyclo(4.2.1) hydrocarbons having a ring system of nine carbon atoms and to methods by which such polycyclic compounds are produced.

It is an object of the present invention to provide a novel class of polycyclic organic compounds and methods for the production thereof. A more particular object is to provide novel hydrocarbons containing a bicyclo(4.2.1) carbocyclic ring system of nine carbon atoms, which ring system is saturated or contains from 1 to 3 ethylenic linkages wherein no bridgehead carbon atom is a member of an ethylenic carbon-carbon bond. An additional object is to provide novel methods for the production of such bicyclic compounds.

It has now been found that these objects are accomplished by processes which comprise the pyrolysis of certain classes of polycyclic compounds possessing a more complex ring system. Such processes provide the desired ring system directly or alternatively provide precursors thereof, from which the desired bicyclic compounds are easily produced.

The novel compounds of the invention comprise the bicyclo(4.2.1)nonanes and the corresponding ethylenically unsaturated bicyclic compounds having from 1 to 3 endo ethylenic linkages, i.e., non-aromatic carbon-carbon double bonds wherein both carbons are members of the carbocyclic ring system. Generically, these compounds are non- to tri-ethylenically unsaturated bicyclo(4.2.1)nonanes. Although numerous positions isomers are available when the bicyclic compound contains ethylenic linkages, preferred compounds of the invention are those non- to tri-ethylenically unsaturated bicyclo(4.2.1)nonanes wherein no bridgehead carbon atom, i.e., no carbon atom common to two or more rings, is a member of an ethylenic linkage. One class of such compounds has from 9 to 89 carbon atoms, preferably from 9 to 40, and is represented by the formula

wherein R independently is hydrocarbon containing no non-aromatic unsaturation, e.g., alkyl, cycloalkyl or aryl, having from 1 to 10 carbon atoms, preferably from 1 to 6, and m represents the number of R substituents and is a whole number from 0 to 8 inclusive, preferably from 0 to 4. In the above-depicted formula, the dotted line designation is employed to indicate possible locations of ethylenic linkages. The designation, as employed herein, generically signifies that the bond between the carbon atoms connected by the dotted line may be a single bond, i.e., a saturated carbon-carbon linkage, or alternatively may be a double bond, i.e., an ethylenic linkage, depending, of course, on whether the bicyclic compound is saturated or mono- to tri-ethylenically unsaturated. It will be appreciated that in accord with the preference for bicyclic compounds which are saturated or unsaturated with endo ethylenic linkages not involving bridgehead carbon atoms, the locations designated by the dotted lines are the only

2

locations which may alternatively be single or double bonds. It will also be observed that the cyclic structure of the molecule precludes any single carbon atom from being a member of two ethylenic linkages, and the compounds of the invention do not contain adjacent ethylenic linkages, i.e., allene moieties. As will be shown hereinafter, by varying the substitution of R groups on reactant molecules, bicyclic compounds possessing R substituents in a variety of locations may be prepared. Preferred, however, are bicyclic compounds of the above-depicted formula wherein each carbon atom of the eight membered ring has no more than a single R substituent, and the 2 and 5 carbon atoms have only hydrogen substituents. It is to be understood that R groups, when present, replace hydrogen substituents that are present in the non-R substituted bicyclic compound, and the remaining valences of carbon atoms that are not substituted with R groups are satisfied with hydrogen substituents.

The bicyclic compounds of the invention are produced by the thermal conversion, i.e., pyrolysis, of hydrocarbon compounds possessing a more complex ring system. Preferred compounds of this type are non- to mono-ethylenically unsaturated tricyclo(4.2.1.0^{2,5})non-3-enes or precursors thereof. By non- to mono-ethylenically unsaturated tricyclo(4.2.1.0^{2,5})non-3-ene is meant a tricyclonon-3-ene incorporating the (4.2.1.0^{2,5}) ring system with an ethylenic linkage between the 3 and 4 carbon atoms, and from 0 to 1 additional ethylenic linkages. In accordance with the preference for bicyclic products possessing ethylenic linkages not involving bridgehead carbon atoms, it is preferred that the additional ethylenic linkage, if additional ethylenic linkage is present, also not involve a bridgehead carbon atom. Preferred non- to mono-ethylenically unsaturated tricyclo(4.2.1.0^{2,5})non-3-enes are represented by the formula

wherein R, m and the dotted line designation have the previously stated significance.

One convenient method for preparing the non- to mono-ethylenically unsaturated tricyclo(4.2.1.0^{2,5})non-3-ene reactants is by condensation of an acetylenic hydrocarbon comprising a single carbon-carbon triple bond, the substituents on which are hydrogen or hydrocarbyl having from 1 to 10 carbon atoms, preferably 1 to 6, and containing no non-aromatic unsaturation, with a bicyclo(2.2.1)-hepta-2-ene which alternatively may possess an additional endo ethylenic linkage not involving a bridgehead carbon atom, i.e., alternatively may be a bicyclo(2.2.1)hepta-2,5-diene. The condensation is effected in the presence of a transition metal, preferably nickel, complex as catalyst, which complex contains the metal in a reduced oxidation state, preferably 0, and is stabilized by complex formation with stabilizing ligands such as phosphines, stibines, arsines, carbon monoxide and the like, but is preferably stabilized with (trihydrocarbyl)phosphite, particularly trialkylphosphites. A particularly useful catalyst for this condensation is tetrakis[tri(2-ethylhexyl)-phosphite]nickel(0). The condensation process is represented by the following equation.

The bicyclo(2.2.1)hepta-2,5-dienes are conveniently prepared by condensation of a cyclopentadiene and an acetylenic hydrocarbon, such as by the process described in U.S. 2,875,256 issued February 24, 1959, to Hyman et al. In like manner, bicyclo(2.2.1)hepta-2-enes are prepared by analogous reaction of cyclopentadienes and ethylenic compounds. Although the above equation represents reaction of unsubstituted bicyclic compounds and acetylene, it should be understood that the process is equally applicable to reaction of hydrocarbyl-substituted compounds. For ease of condensation, however, it is preferred that the carbon atoms of at least one ethylenic linkage of the bicyclic reactant be substituted with hydrogens, as is depicted. This production of non- to mono-ethylenically unsaturated tricyclo(4.2.1.0^{2,5})nona - 3 - enes and related materials, as well as the suitable nickel catalysts, is described more fully and is claimed in co-pending application of L. G. Cannell, U.S. Serial No. 355,889, filed of even date.

The non- to mono-ethylenically unsaturated tricyclo(4.2.1.0^{2,5})nona-3-ene is converted to the isomeric non- to mono-ethylenically unsaturated bicyclo(4.2.1)nona-2,4-diene by maintaining the tricyclic reactant at an elevated temperature. Such a thermal conversion is represented by the equation

wherein R, m and the dotted line designation have previously stated significance. Temperatures that are suit-

ably employed for the thermal conversion are from about 200° C. to about 500° C., although pyrolysis temperatures from about 350° C. to about 450° C. are preferred. The thermal conversion is effected at pressures that are subatmospheric, atmospheric or superatmospheric, although the use of pressures other than atmospheric appears to offer little advantage, and utilization of pressures that are substantially atmospheric are preferred. The pyrolysis may be conducted in a batchwise manner as by maintaining the tricyclic reactant at or about reflux temperature and subsequently recovering the pyrolysis products therefrom, as by distillation. It is equivalently useful and generally preferred to conduct the thermal conversion of tricyclic reactant in a continuous process as by passing the tricyclic reactant through a heated tube, together with an inert carrier gas such as nitrogen, helium, argon, steam and the like, and recovering the bicyclic product from the effluent by conventional methods, e.g., fractional distillation.

An alternate modification of the pyrolysis process of the invention comprises the thermal conversion of a precursor of the non- to mono-ethylenically unsaturated tricyclo(4.2.1.0^{2,5})-nona-3-ene. The preferred precursor type is a pentacyclo-(8.2.1^{4,7}.0^{2,9}.0^{3,8})tetradeca - 5,11 - diene, which may also be referred to as a bicyclo(2.2.1)hepta-2,5-diene dimer. Bicyclo-(2.2.1)hepta-2,5-diene is capable of dimerizing to produce a variety of products, depending in part upon the reaction conditions employed. In the presence of certain transition metal complex catalysts, particularly those complexes of nickel wherein the metal is present in a reduced oxidation state and is complexed with stabilizing ligands such as trihydrocarbyl-

phosphite, the bicycloheptadiene dimerizes to produce the pentacyclo(8.2.1.1^{4,7}.0^{2,9}.0^{3,8}) - tetradeca - 5,11 - diene product. The process for this dimerization, which is illustrated by the following equation, is described more fully in co-pending application of Muller et al., Serial No. 257,090, filed February 8, 1963.

While the equation illustrates the reaction of unsubstituted bicycloheptadiene, it should be understood that the bicycloheptadiene may be substituted with up to mR substituents wherein R and m have the previously stated significance. For ease of condensation, however, it is preferred that the carbon atoms of at least one ethylenic linkage of the bicycloheptadiene be substituted with hydrogens.

The bicycloheptadiene dimer is converted to a mixture of products by pyrolysis. Without wishing to be bound by any specific theory, it appears that the initial pyrolysis products are a cyclopentadiene and a tricyclo(4.2.1.0^{2,5})-nona-3,7-diene, which latter compound at least in part undergoes ring opening to the bicyclic compounds of the invention, as is described hereinbefore. The products of the pyrolysis of the pentacyclo-(8.2.1.1^{4,7}.0^{2,9}.0^{3,8})tetradeca-5,11-diene therefore comprise a mixture of tricyclo(4.2.1.0^{2,5})-nona - 3,7 - diene and bicyclo(4.2.1)nona-2,4,7-triene in varying proportions, together with an amount of cyclopentadiene equimolar with the total of bicyclic and tricyclic products. This pyrolysis is represented by the following equation

wherein R and m have the previously stated significance. Although the pentacyclic reactant is depicted as having a planar configuration, it will be appreciated that various cis-trans and endo-exo isomers of the pentacyclotetradeca-diene will be formed during bicycloheptadiene dimerization, and the ease of pyrolysis will be somewhat variable. The pyrolysis is conducted at temperatures from about 200° C. to about 500° C., although temperatures from about 250° C. to about 475° C. are preferred. The pyrolysis is typically conducted at atmospheric or superatmospheric pressures, although utilization of pressures that are substantially atmospheric are preferred.

The thermal conversion of the pentacyclotetradeca-diene is conducted in a batchwise manner, as by maintaining the reactant at an elevated temperature and removing the pyrolysis products therefrom by distillation, or alternatively the pyrolysis is conducted in a continuous manner as by passing the pentacyclic reactant through a heated tube, preferably employing an inert carrier gas, and recovering the desired product from the effluent. The ratio of tricyclononadiene to bicyclononatriene in the product mixture is determined somewhat by the pyrolysis temperature and the residence time. At temperatures below about 300° C. and short residence times, the tricyclononadiene is the predominant polycyclic product by a ratio of about 7:1. When higher temperatures are employed, e.g., about 400° C., the bicyclononatriene is the major polycyclic product, being formed in a ratio of about 3:1 to the tricyclononadiene. Upon this basis, it is considered likely that the initial pyrolysis product is the tricyclononatriene which undergoes more extensive ring opening under more vigorous pyrolysis conditions.

The production of bicyclo(4.2.1)nona-2,4,7-triene from bicycloheptadiene dimer is therefore favored by higher pyrolysis temperatures and longer residence times. Good results are obtained by employing an initial pyrolysis temperature of from about 300° C. to about 500° C., preferably from about 350° C. about 450° C., in a one-step thermal conversion, although it is equivalently useful and often preferable to employ two-step conversion, as by utilizing a comparably low initial pyrolysis temperature, e.g., 200° C. to 300° C., and subsequently conducting a second thermal conversion at a higher temperature, e.g., 350° C. to 450° C., to promote more extensive isomerization, i.e., ring opening, to the desired bicyclic nonatriene. Subsequent to the thermal conversion, the product mixture is separated and the bicyclo-nonatriene recovered by conventional methods such as fractional distillation, selective extraction and the like.

As described above, thermal conversion of the non-to mono-ethylenically unsaturated tricyclo(4.2.1.0^{2,5})nona-3-ene or precursor thereof results in the production of bicyclo(4.2.1)nona-2,4-dienes which may have an additional ethylenic linkage between the 7 and 8 carbon atoms, depending upon the extent of unsaturation of the reactant. These products are readily converted to the corresponding saturated hydrocarbon, or if hydrogenation is terminated before complete saturation, to compounds which possess a lesser degree of unsaturation. For example, a bicyclo(4.2.1)nona-2,4,7-triene is typically converted to a mixture of predominantly bicyclo(4.2.1)nona-2,7-diene, bicyclo(4.2.1)nona-3,7-diene and bicyclo(4.2.1)non-2-ene by incomplete hydrogenation, and a bicyclo(4.2.1)nona-2,4-diene is typically converted to a mixture of bicyclo(4.2.1)non-2-ene and bicyclo(4.2.1)non-3-ene. Either reactant or any of the partial hydrogenation products may be converted to the saturated bicyclo(4.2.1) nonane by allowing hydrogenation to proceed to completion. Hydrogenation is conveniently effected by contacting the unsaturated bicyclic compounds with molecular hydrogen in the presence of a conventional hydrogenation catalyst. Typical of such catalysts are transition metals of Group VIII of the Periodic Table, e.g., platinum, palladium and rhodium, or oxides thereof, which may be unsupported or supported upon inert carriers such as carbon, alumina and the like, as well as mixed oxide catalysts such as copper chromite.

It will be apparent from the above discussion that a variety of substituted and unsubstituted bicyclic compounds may be produced. In the nomenclature of such compounds, as well as the reactants employed for the production thereof, conventional numbering of the ring systems has been employed, as further illustrated by the following formula.

Typical products of the process of the invention, numbered according to this system, include

bicyclo(4.2.1)nona-2,4,7-triene,
bicyclo(4.2.1)nona-2,4-diene,
bicyclo(4.2.1)non-2-ene,
bicyclo(4.2.1)non-3-ene,
3,4-dimethylbicyclo(4.2.1)nona-2,4,7-triene,
7,8-diethylbicyclo(4.2.1)nona-2,4-diene,
3-propylbicyclo(4.2.1)non-3-ene,
7-benzylbicyclo(4.2.1)nona-2,4,7-triene,
3-phenylbicyclo(4.2.1)non-2-ene,
9,9-dimethylbicyclo(4.2.1)nona-2,4,7-triene,
1-ethylbicyclo(4.2.1)nona-2,7-diene and the like.

The novel ring-unsaturated compounds of the invention are useful in a variety of applications as chemical

intermediates. By employing the ethylenic linkages as reactive sites, the compounds of the invention may be polymerized with reactive unsaturates to form elastomers and thermoplastics. They are useful as ligands in the production of metal complexes, as dienes or dienophiles in Diels-Alder condensations, depending upon the number and the location of the ethylenic linkages, and additionally may be epoxidized to form useful epoxy resin precursors. The unsaturated linkages may be hydrated or hydroxylated to form novel alcohols from which useful conventional derivatives may be produced. In addition, the saturated bicyclo(4.2.1)nonanes are useful as special solvents, and high energy fuels.

To further illustrate the novel process of the invention and the novel products obtained thereby, the following examples are provided. It should be understood that they are not to be regarded as limitations, as the teachings thereof may be varied as will be understood by one skilled in this art.

Example I

Pentacyclo(8.2.1.1^{4,7}.0^{2,5}.0^{3,8})tetradeca - 5,11 - diene (bicycloheptadiene dimer) was fed at a constant rate into a heated, glass tubular reactor with helium which served as a carrier. Within 70 minutes, 7.4 g. of bicyclo(2.2.1)-hepta-2,5-diene dimer had been introduced. The residence time was 0.16 minute and the temperature within the tube was 400° C. The liquid product, 7.2 g., was recovered and by analysis was shown to consist of 10% by weight tricyclo(4.2.1.0^{2,5})nona - 3,7 - diene, 44% by weight bicyclo(4.2.1)non - 2,4,7 - triene 29% by weight cyclopentadiene and 17% by weight recovered feed.

The polycyclic products were separated by distillation under reduced pressure. Bicyclo(4.2.1)nona-2,4,7-triene, B.P. 99° C. at 106 mm., η_{D}^{20} 1.5357, was obtained as one fraction in a purity of 99% as determined by gas-liquid chromatographic analysis. The molecular weight of this compound was shown by mass spectroscopy to be 118, and the nuclear magnetic resonance spectrum was consistent with the above formula. The bicyclo(4.2.1)-nona-2,4,7-triene is a colorless liquid and is miscible with common organic solvents.

Example II

The procedure of Example I was repeated using 31.77 g. of the bicycloheptadiene dimer and employing a pyrolysis temperature of 400° C. and a residence time of 0.14 minute. Gas-liquid chromatographic analysis of the effluent indicated the product mixture consisted of 12% by weight tricyclo(4.2.1.0^{2,5})nona - 3,7 - diene, 35% by weight bicyclo(4.2.1)nona - 2,4,7 - triene, 26% by weight cyclopentadiene and 27% by weight recovered feed.

Example III

The procedure of Example I was repeated, except that a pyrolysis temperature of 525° C. was employed. The principal products obtained were allylbenzene and indene; little tricyclo(4.2.1.0^{2,5})nona-3,7-diene or bicyclo(4.2.1)-nona-2,4,7-triene were observed.

Example IV

Tricyclo(4.2.1.0^{2,5})nona-3,7-diene was introduced into a Vycor tube maintained at 400° C., with a residence time therein of 0.11 minute. Gas-liquid chromatographic analysis of the effluent indicate a conversion of 92% to bicyclo(4.2.1)nona - 2,4,7 - triene, which product was identical with that produced by the procedure of Example I.

Similar results are obtained when 3,4-diphenyltricyclo(4.2.1.0^{2,5})nona-3,7-diene is employed as reactant.

Example V

3,4-dimethyltricyclo(4.2.1.0^{2,5})non-3-ene was introduced into a heated tube maintained at 500° C. at a rate sufficient to provide a residence time of 0.19 minute. Nitrogen was employed as a carrier gas. The feed olefin was converted to an extent of 94% to a mixture of prod-

ucts, 89% by weight of which was 3,4-dimethylbicyclo(4.2.1)nona-2,4-diene, B.P. 133° C. at 80 mm. n_D^{20} 1.5274. Mass spectroscopy established a molecular weight of 148 for the product. An ultraviolet spectrum (in methanol) included a maximum at 264 m μ which is characteristic of conjugated double bonds, and the nuclear magnetic resonance spectrum was consistent with the above formula.

Example VI

To an 84 ml. autoclave, 4.430 g. of bicyclo(4.2.1)nona-2,4,7-triene was charged together with a small amount of 10% palladium-on-activated-charcoal catalyst. The reactor was maintained at 50° C. and hydrogen was introduced to give an initial pressure of 400 p.s.i.g. Reaction ceased when the hydrogen uptake corresponded to 110 millimoles (theoretical uptake is 111 millimoles) and the product, bicyclo(4.2.1)-nonane was recovered and purified by sublimation to afford a white solid, M.P. 81° C. Mass spectroscopy confirmed the uptake of three moles of hydrogen per mole of unsaturate, and the nuclear magnetic resonance spectrum was consistent with the above formula.

Analysis.—Calc.: C, percent wt., 87.1; H, percent wt., 12.9. Found: C, percent wt., 87.3; H, percent wt., 12.7.

Example VII

Bicyclo(4.2.1)nona-2,4,7-triene was partially hydrogenated over a copper chromite catalyst under an initial hydrogen pressure of 400 p.s.i.g. and a temperature of 150° C. In separate experiments, hydrogenation was allowed to proceed until hydrogen uptakes of 1.0 and 1.6 moles of hydrogen per mole of bicyclononatriene had been reached. The three partial hydrogenation products were separated by preparative gas-liquid chromatographic techniques and examined utilizing both chemical and physical means. In each case, retention of the bicyclo(4.2.1) ring system was confirmed by a further experiment wherein hydrogenation over the copper chromite catalyst was allowed to proceed to completion to yield bicyclo(4.2.1)nonane.

The mass spectra of the partial hydrogenation products allowed determination of the extent of hydrogenation from consideration of the parent ion peaks, and the nuclear magnetic resonance spectrum allowed unambiguous assignment of structure. The two principal products obtained in good yield from the uptake of one mole of hydrogen per mole of bicyclononatriene were bicyclo(4.2.1)-nona-3,7-diene and bicyclo(4.2.1)nona-2,7-diene, both of which products are colorless liquids with refractive indices of n_D^{20} 1.5045 and n_D^{20} 1.5093 respectively. The principal product resulting from the uptake of two moles of hydrogen per mole of bicyclononatriene was bicyclo(4.2.1)non-2-ene, a white solid, M.P. 35° C.

I claim as my invention:

1. The process for the production of polycyclic hydrocarbon which comprises pyrolyzing tricyclo(4.2.1.0^{2,5})non-3-ene having from 0 to 1 additional endo ethylenic

linkage connecting non-bridgehead carbon atoms, having as the only non-hydrogen ring substituents from 0 to 8 hydrocarbyl substituents independently having from 1 to 6 carbon atoms, said hydrocarbyls having only aromatic unsaturation, at a temperature from about 200° C. to about 500° C., and recovering from the resulting product mixture a bicyclo(4.2.1) hydrocarbon.

2. The process for the production of polycyclic hydrocarbon which comprises pyrolyzing tricyclo(4.2.1.0^{2,5})nona-3,7-diene having from 9 to 40 carbon atoms and having as the only non-hydrogen ring substituents from 0 to 8 hydrocarbyl substituents independently having from 1 to 6 carbon atoms, said hydrocarbyls having only aromatic unsaturation, at a temperature from about 350° C. to about 450° C., and recovering from the resulting product mixture a bicyclo(4.2.1) hydrocarbon.

3. The process for the production of bicyclo(4.2.1)nona-2,4,7-triene which comprises pyrolyzing tricyclo(4.2.1.0^{2,5})nona-3,7-diene at a temperature from about 350° C. to about 450° C.

4. The process for the production of bicyclo(4.2.1)nona-2,4-diene which comprises pyrolyzing tricyclo(4.2.1.0^{2,5})non-3-ene at a temperature from about 350° C. to about 450° C.

5. The process for the production of bicyclo(4.2.1)nona-2,4,7-triene which comprises pyrolyzing pentacyclo(8.2.1.1^{4,7}.0^{2,9}.0^{3,8})tetradeca-5,11-diene at a temperature from about 200° C. to about 500° C. and recovering from the resulting product mixture said bicyclononatriene.

6. The process for the production of bicyclo(4.2.1)nona-2,4,7-triene which comprises initially pyrolyzing pentacyclo(8.2.1.1^{4,7}.0^{2,9}.0^{3,8})tetradeca-5,11-diene at a temperature from about 200° C. to about 300° C., subsequently pyrolyzing the resulting product mixture at a temperature from about 350° C. to about 450° C., and recovering from the resulting product mixture said bicyclononatriene.
